(57) **CLAIM**

The ornamental design for a jewelry bead, as shown and described.

DESCRIPTION

FIG. 1 is a perspective view of the centrally located body of a jewelry bead showing my new design, it being understood that the top and bottom edges have been removed for ease of illustration and that the body is the same in both embodiments as described below;

FIG. 2 is a side elevational view of FIG. 1;

FIG. 3 is an end view of FIG. 1;

FIG. 4 is a perspective view of a jewelry bead showing the first embodiment of my new design;

FIG. 5 is a side elevational view of FIG. 4;

FIG. 6 is an end elevational view of FIG. 4;

FIG. 7 is a perspective view of a jewelry bead showing the second embodiment of my new design;

FIG. 8 is a side elevational view of FIG. 7; and,

FIG. 9 is an end elevational view of FIG. 7.

The cylindrical portion in the center of the design is identical in both embodiments, including the top end and bottom end views. The broken lines of FIGS. 1, 2, and 3 show where a rim design is applied. FIGS. 4, 5, and 6 show an embodiment with a first rim design. FIGS. 7, 8, and 9 show an embodiment with a second rim design.

It being understood that the broken lines in FIGS. 1-3 are for illustrative purposes only and form no part of the claimed design.
